UNITED STATES PATENT OFFICE.

WARREN S. JOHNSON, OF WHITEWATER, ASSIGNOR OF ONE-HALF TO
WILLIAM PLANKINTON, OF MILWAUKEE, WISCONSIN.

THERMO-PNEUMATIC TEMPERATURE-REGULATOR.

SPECIFICATION forming part of Letters Patent No. 314,027, dated March 17, 1885.

Application filed June 20, 1884. (No model.)

To all whom it may concern:

Be it known that I, WARREN S. JOHNSON, of Whitewater, in the county of Walworth, and in the State of Wisconsin, have invented 5 certain new and useful Improvements in Thermo-Pneumatic Temperature-Regulators; and I do hereby declare that the following is a full, clear, and exact description thereof.

My invention relates to a class of inventions 10 used to control the temperature of apartments by automatically cutting off or admitting the supply of heat; and it consists in certain peculiarities of construction, as will be fully set forth hereinafter.

15 In the drawings, Figure 1 is a vertical longitudinal section of the main valve which closes the steam or other passage, and of the expansible chamber connected therewith, together with a side elevation, partly in section, of the 20 thermostat which serves to operate the valves which control the admission of air under pressure to the said expansible chamber, as well as a view of the reservoir for compressed air and the pipe-connections: Fig. 2 is a partly-sectional elevation of a modified form of thermostat, and Fig. 3 is an enlarged detail sectional view of part of the device shown by Fig. 2.

25 In my present invention I utilize the expansion or contraction of substances resulting from a change of temperature to open or close air-valves which, by admitting compressed air to expansible chambers, serve to actuate the main valves which control the supply of heat.

30 Heretofore, so far as known to me, thermostats have been used for the purpose of controlling passages only in two ways: first, by moving the main valves directly, as in damper-regulators for furnaces, and, secondly, by 35 closing an electric circuit, which in turn served to operate the main valve. In a previous invention of mine for an "Electric Valve for Regulating Temperature," &c., for which I filed an application for Letters Patent on March 10, 40 1884, I used the thermostat to control an electric current, which in turn controlled the admission to or release from an expansible chamber of steam, gas, or other fluid, said expansible chamber by its movements serving to 45 control the main valve. In my present invention,

however, I discard the intermediate use of electricity for accomplishing the ultimate design and actuate the valves for compressed air or other gas by the direct utilization of the mechanical effects of the expansion or contraction of the substances of which the thermostat is formed. 55

I will first describe my main valve and expansible chamber.

A is the valve-body or valve-housing; B, the 60 valve-disk, described in detail hereinafter, and c the seat for the valve-disk; C, the packing-box, through which the stem D passes.

E is a follower or packing-nut, screw-threaded, as shown, and designed to compress the 65 packing e in the packing-box c when necessary to prevent a leak. F and G are respectively the inlet and outlet couplings for connection with the steam or other passages.

H is a piece of the shape of an inverted saucer, fastened to the upper end of the stem D. 70

I is a ring, which is connected to the top of the packing-box C by means of a spider composed of the right-angled arms a a, inside of which spider the piece H on the stem D has 75 vertical play, being kept normally at the greatest distance from the top of the packing-box C that the pressure above (hereinafter described) will permit by means of the spiral spring b, surrounding the stem D. 80

J is a piece of the same general shape as the piece H, except that it has a right-angled flange, L, around its periphery, by means of which it is secured, by the bolts or screws i i, to the ring I, a flexible diaphragm, K, made 85 of cloth or rubber—preferably the latter—being secured between the adjacent surfaces of the flange L and ring I firmly, so as to make everywhere an air-tight joint, forming an expansible chamber, h, above the diaphragm K. 90

M is a tube leading into an opening, j, formed in a boss or projection on the exterior of the piece K, the said opening extending into the expansible chamber.

The valve-disk B is connected to its stem D 95 in this manner: The lower end of the stem is reduced and screw-threaded, as at d, and this end is screwed into a headed nut, f, the flanged head of which is of greater diameter than the bore in another nut or collar, g, which is first 100

slipped over the nut *f* before the stem *D* is screwed to place, and then the nut *g*, whose exterior is screw-threaded, is screwed within the hollow upper part of the valve-disk *B*, whereby the said disk is substantially swiveled or loosely connected to its stem, as shown in Fig. 1.

The upper part of the piece *J* (which I designate the "umbrella-shaped piece") is made of increased thickness and centrally perforated, and the inner surface of the collar *l*, thereby formed, is screw-threaded to receive the correspondingly screw-threaded lower part of the stem-guide *O*, which supports the auxiliary stem *N*. This guide *O* has a ring or flange, *o*, resting upon top of the collar *l*, and is centrally perforated (longitudinally) to receive the said stem *N*, the lower part of which has exterior screw-threads working in corresponding screw-threads within the lower part of the described central bore of the stem-guide *O*. The upper exterior part of said guide *O* is likewise screw-threaded to receive the screw-cap *P*, perforated for the admission of the stem *N*, and suitable packing, *p*, is interposed between the under surface of the top of this cap and the top of the guide *O*. The base of the auxiliary stem *N* is furnished with a flange, *n*, and its upper end is provided with a wheel or handle, *Q*, secured to the stem *N*, as by screw *q*.

R *R'* represent the different substances—such, for example, as steel and vulcanite, respectively—of which a thermostat is composed. This thermostat is rigidly secured at *r* to some convenient part of the room the temperature of which is to be regulated. The part *R* is bifurcated at its lower end, the fork thereby formed in the form shown in Fig. 1 having the tine *r'* with square end, and the tine *r''* with an inward-extending right-angled catch at its end.

S is a reservoir containing air under pressure, and having a pipe, *s*, leading to a valve-chamber, *T*, having two valve-seats, *t* and *t'*, opposite each other, as well as an outlet, *t''*, communicating with the pipe or passage *m*, which leads to the pipes or passages *M* *j* of the expansible chamber, already described.

U is a disk mounted on a shaft, *U'*, and having an offset, *u*, adapted to engage alternately with one or the other of the tines *r'* or *r''*, as hereinafter described. The said disk also has a pin, *u'*, projecting therefrom, from which is suspended a link, *u''*, which in turn carries a valve-stem, *V*, bearing a two-faced valve, *v v'*, adapted to be carried against the valve-seats *t t'*, respectively.

In this form of thermostat I employ sufficient clock-work, as shown by the wheel *1*, mounted on the shaft *U'*, which carries the disk *U*, and the wheel *2*, meshing therewith, and the spring *3*, to actuate the disk *U* by the unwinding force of the spring *3*, and permit it to make a half-revolution at a time from the tine *r'* to the tine *r''*, and vice versa, whenever the expansion or contraction of the

thermostat frees the offset *u* from contact with either tine.

The operation of my device will be readily understood from the foregoing description and illustration of its construction: The compressed air from the reservoir *S* fills the pipe *s*, but is prevented from entering the valve-chamber *T* so long as the valve-head *v* is pressed against its seat *t*, as shown in Fig. 1. In this figure my device is represented as at a time when the steam or other heat passages are open, the main valve *B*, controlling the same, being raised from its seat *c*. Should the temperature in the room become raised above its present condition, the thermostat will expand and move to the left, thereby releasing the tine *r'* from contact with the offset *u* on the disk *U*, when the unwinding force of the spring *3* will set the train of clock-work in motion, and the wheel *2* will turn the wheel *1*, and the latter, being fast on the same shaft, *U'*, that carries the disk *U*, will cause the said disk to make a half-revolution until its offset *u* encounters the stop on the other tine, *r''*, the link *u''* and valve-stem *V* being thereby raised, so that the valve-head *v* now bears against its seat *t'*, freeing the seat *t* from contact with the valve-head *v* and enabling the compressed air in the pipe *s* to enter the valve-chamber *T*, and thence to pass out through the outlet *t''* into the pipes or passages *m*, *M*, and *j*, into the expansible chamber *h*, depressing the flexible diaphragm *K*, and with it the saucer-piece *H* and valve-stem *D*, (against the force of the spring *b*.) thereby forcing the main valve-disk *B* against its seat *c*, closing the inlet-passage of the steam or other heating medium. Conversely, when the temperature of the room falls below the required point by reason of such shutting off of the steam or other heating medium, then the thermostat will contract and move to the right, which action will free the catch on the tine *r''* from contact with the offset *u* on the disk *U*, and the said disk will make another half-revolution back to the position shown in Fig. 1 until stopped by the tine *r'*, when the valve-head *v* will again rest on its seat *t*, thereby shutting off any further supply of compressed air from the reservoir *S*, and the compressed air in the expansible chamber *h* will seek an outlet back through the passages *j*, *M*, *m*, and *t''*, and out of the valve-chamber *T*, through the opening above the valve-seat *t'*, into the room, as indicated by the arrows, while at the same time, as the compressed air escapes from the expansible chamber *h*, the spring *b*, operating against the under side of the saucer-piece *H*, raises it and the stem *D*, and opens the valve *B* to the fullest extent, enabling the steam or other heating medium to again enter at the inlet *F*, as before. In Figs. 2 and 3 I show a slight modification of the thermostat, together with devices for operating the main valve therefrom, dispensing with the clock-work shown in Fig. 1. In this form of my device I have shown the several parts in the positions they would occupy

when the room is too warm and with the thermostat expanded, and hence when the main valve B is closed against its seat *c*, or, in other words, in just the reversed condition 5 from that shown by the thermostat and its connections in Fig. 1, and with the further difference that the valve-seat *t'* is shown here as exterior to the valve-chamber T, instead of being in the interior of said chamber, as in Fig. 1.

10 The compressed air from the reservoir S passes into the interior of the chamber T, as first described, and the valve *v'* being against its seat *t'*, the said air moves out of the chamber through outlet *t²* into the pipe *m*, and thence 15 through M and *j* into the expansible chamber *h*, all as before set forth, to close the valve B and shut off the admission of steam or other medium, and thereby cool the apartment. Conversely, when the room becomes too cool, 20 the thermostat contracts and moves to the right, thereby freeing the valve *v'* from contact with its seat *t'*, and enabling the compressed air to escape out into the room and the main valve B to open, while the plunger 25 *v²* of the valve-stem V, that is attached to the tine *r'* of the thermostat, will thereby be also carried to the right, pressing against a flexible diaphragm, *v*, (corresponding to the valve-head *v* in Fig. 1,) over the inner end of the 30 hollow nut *v³*, within which the plunger *v²* works, and pressing the said diaphragm *v* against the valve-seat *t* at the terminus of the passage *s*, completely shutting off the supply of compressed air until the room again becomes 35 too warm, and so on continuously and automatically.

By means of the hollow nut *v³*, above named, I am enabled to make a nice adjustment of the valve-action, and as the valve-stems V V 40 in this form of my device are made of spring-steel or analogous material having a spring action, the right-hand stem, which bears the valve-head *v'*, has a tension which keeps it firmly in place against the seat *t'* until after 45 the plunger *v²* on the opposite stem has forced the diaphragm *v* against the seat *t* and firmly closed that port.

The object of the auxiliary stem N is to enable the valve B to be closed by hand at any 50 time desired, instead of automatically, and it operates by simply turning the wheel or handle Q, which serves to screw the stem downward through the stem-guide O, when the flange *n* at the base of the stem N will bear 55 down on the diaphragm K and depress the saucer-piece H and stem D, and thereby force the valve-disk B to its seat. This auxiliary stem serves the same purpose as that shown in my former application, to which reference 60 has been made hereinbefore; but its construction and attachment are entirely different.

Having thus described my invention, what I claim as new, and desire to secure by Letters Patent, is—

65 1. The combination, with a main valve controlling steam or analogous passages, and an expansible chamber for operating said valve,

of a thermostat and a double valve operated directly thereby, a reservoir of compressed air, and suitable pipe connections or passages, 70 substantially as described, whereby the main valve will be operated by the compressed air and the passage of the latter to and from the expansible chamber be controlled by the action of the thermostat, substantially as set 75 forth.

2. In a temperature-regulator, the combination of a thermostat whose free portion is moved by a change of temperature in the surrounding medium, a valve mechanism operated by the mechanical action of said thermostat, a reservoir of air or other gas under pressure, the escape of the air or gas from said reservoir being controlled by the mechanical action of said thermostat through said valve 85 mechanism, an expansible chamber whose inlet and outlet are controlled by said valve mechanism and a valve operated by the expansion of said chamber, said valve by its movements controlling a steam or other passage, whereby a rise of temperature in the medium surrounding the thermostat operates the outlet to said reservoir and inlet to said expansible chamber, so that the chamber is expanded and the valve governing the steam 90 or other passage is operated in one direction, and a fall of temperature in the surrounding medium through the mechanical action of the thermostat serves to close the inlet to said expansible chamber and opens the outlet to 95 said chamber, whereby the said valve which controls the steam or other passage is operated in the other direction, substantially as set forth.

3. In a temperature-regulator, the combination of a thermostat having fork or projections at its free end, and actuating mechanism, substantially as described, with a valve-chamber having inlet and outlet ports, and a double valve adapted to close one of said ports 100 and open the other, according as the thermostat expands or contracts, substantially as set forth.

4. In a temperature-regulator, the combination of a valve adapted to close a steam or 105 other passage, an expansible chamber having a flexible wall and a rigid backing, a valve-stem having a disk secured to the end opposite the valve, said stem passing through the packing-box of the valve-body, and a spring 110 interposed between the packing-box and disk and surrounding said stem, substantially as set forth.

5. In a temperature-regulator, the combination of a valve adapted to close a steam or 115 other passage, an expansible chamber having a flexible wall and a rigid backing, a valve-stem passing through the packing-box of the valve body or housing and having a disk secured to the end opposite the valve, a spring 120 interposed between the packing-box and disk and surrounding said stem, and an auxiliary stem bearing a flange on its inner end and a wheel or handle on its outer end, and having 125

exterior screw-threads working in corresponding threads in the bore of a stem-guide through which it passes, said stem-guide being secured within a central perforation of the rigid backing of the expandible chamber, substantially as set forth.

6. In a temperature-regulator, the combination of the body or housing A, having packing-box C and inlet and outlet coupling connections F and G and valve-seat *c*, spider *a a*, ring I, and the backing J and diaphragm K, forming expandible chamber *h* between them, stem D, having disk H secured to one end and valve-disk B swiveled or loosely connected to the other end, and the spring *b*, interposed between the disk H and packing-box C, substantially as set forth.
15. 7. In combination with the thermostat R R',

having the forked ends *r' r''*, the disk U, mounted on shaft U' and provided with offset *u* and pin *u'*, the valve-chamber T, having inlet-port with valve-seat *t*, and outlet-port with valve-seat *t'*, the link *u''*, valve-stem V, and two-faced valve *v v'*, and suitable clock-work mechanism, and pipes or passages to and from the valve-chamber, substantially as set forth.

In testimony that I claim the foregoing I have hereunto set my hand at Milwaukee, in the county of Milwaukee and State of Wisconsin, in the presence of two witnesses.

WARREN S. JOHNSON.
